UNITED STATES PATENT OFFICE.

WILLIAM KAHRE, OF WHARTON, NEW JERSEY.

DOBBY FOR LOOMS.

971,846.

Specification of Letters Patent.

Patented Oct. 4, 1910.

Application filed December 9, 1909. Serial No. 532,149.

To all whom it may concern:

Be it known that I, WILLIAM KAHRE, a citizen of the United States, residing in Wharton, Morris county, and State of New Jersey, have invented a certain new and useful Improvement in Dobbies for Looms; and I do hereby declare the following to be a full, clear, and exact description of the invention, such as will enable others skilled 10 in the art to which it appertains to make and use the same, reference being had to the accompanying drawings, and to letters of reference marked thereon, which form a part of this specification.

15 The principal object of this invention is to provide a doby for looms practically adapted for performing such service as the control of the shuttle-boxes, where the boxes to be operated are two or more in number.

20 My object may be more particularly indicated as follows: In an ordinary doby the jacks or their equivalents are movable to but two positions, the one the idle position, wherein they stand held against a stop 25 under the pull of the harness or the like to be controlled, and the other the working position, wherein they are held by the floating levers so long as said levers, through their hooks, are oscillated from the reciprocating knives. Since, therefore, only two 30 positions of the jacks can be attained in the use of an ordinary doby, it is impossible to use such a doby for accomplishing more than a corresponding number of positions 35 as to the part to be actuated, for instance a box structure having three or more boxes.

The object in hand—to provide a doby capable of setting its jacks or other actuated parts at any of two or more positions—I 40 have found may be accomplished by constructing the parts so as to permit lost motion in the train of elements comprising the knives, the box structure or other member to be actuated from them and the parts for 45 transmitting motion from the former to the latter, and by providing for regulating such lost motion so as to obtain any of the several positions which the member actuated is calculated to assume.

50 In the adaptation of my invention herein shown and described, the lost motion referred to is accomplished as follows: The doby has a plurality of jacks and corresponding floating levers and hooks. One of the levers 55 has a fixed pivot on its jack; this jack will

therefore serve for deriving two positions of the box structure (say the uppermost and lowermost boxes thereof); when it is in its idle position, say, it will "call" the uppermost box and when in its working or oscillating position, it will "call" the lowermost box. Another of these levers has a slot-and-pin connection with its jack; the slot is of such extent that, allowing lost-motion, the corresponding jack can not be advanced by 60 its lever (when the latter assumes its working or oscillating position) as far as the first lever advances its jack. An intermediate jack position, which may be made to correspond to the working position of a 65 third box, is thus produced. Other intermediate jack positions, corresponding to other boxes, may in like manner be secured, depending on the respective lengths of the slots.

70 In view of the foregoing my invention consists broadly in a means in a loom for effecting the movements of a member to be shifted to two or more positions, such as a box structure, the same comprising, with 75 80 knives adapted to reciprocate synchronously in reverse directions, a train of parts adapted to transmit movement from the knives to said member and having a lost motion connection between two of its parts, 85 said train comprising hooks respectively engageable with the knives and a lever pivotally connecting the hooks.

85 In the accompanying drawings, the improved doby has been shown as adapted to 90 shift a box structure or the like to four different positions, Figure 1 showing the improved doby in operative position on a loom frame and in vertical section in a plane extending transversely of the loom, the parts 95 appearing in this view being those which are utilized to bring the No. 2 box of a box structure A into position and the said structure appearing diagrammatically; Fig. 2 is another similar sectional view taken in a 100 different plane so as to show those parts which are utilized to bring the No. 3 box into position; and, Fig. 3 is another similar sectional view taken in a different plane so as to show those parts which are utilized to 105 bring the No. 4 box into position, it being remarked that the No. 1 position of the box structure corresponds to that position which the parts referred to assume when standing idle.

a is the frame of the loom and *b* the frame of the dobby. In the dobby frame *b* are arranged to slide synchronously in reserve directions the knives *c*.

5 *d* designates a horizontal shaft forming a part of the frame *b* and serving as a fulcrum for the jacks *e*, *e'*, *e''* which, in their rest or idle positions, engage a bar *f* carried by brackets *g* projecting from the frame *b*. *h*, *h'* and *h''* are the jack-levers, the same being pivotally connected with the jacks *e*, *e'* and *e''*, respectively, as herein-after explained. *i* denotes stops against which these jack-levers may abut, the same being adapted to be engaged by the upper and lower ends of the jack-levers.

10 *j* and *j'* designate an upper and a lower hook pivotally connected to each jack-lever *h*, *h'* and *h''*, said hooks being adapted for 20 movement together vertically by being both supported by one of several lifting wires *h* whose vertical movements are effected by one of several levers *l* corresponding in number to the wires and controlled from a suitable pattern mechanism *m*.

15 The knives *c* are reciprocated, through the medium of suitable links *n*, from a lever *o* fulcrumed at *p*, in the usual manner.

20 Referring, now, to Fig. 3, the jack-lever *h* is pivotally connected to its jack *e* by a pivoting pin *q* which is fixed with respect to each of these two parts. The jack *e* is therefore capable of assuming either the 25 position shown in full lines or that shown in dot-and-dash outline, according to whether the hooks are disengaged from the knives, allowing the jack to rest against its stop *f*, or whether the hooks are engaged with the knives and the jack-lever is therefore being 30 vibrated around a relatively advanced fulcrum. As already stated, the dot-and-dash outline position of the jack *e* corresponds to the position where box No. 4 of the box structure *A* in Fig. 1 is alined with a fixed 35 plane *B*, which may represent the surface of the batten; while the full-line position of the jack corresponds to the position where box No. 1 is alined with the plane *B*.

40 In Fig. 2, the pivoting pin *q'* is fixed with respect to one of the parts *e'* and *h'* and is passed through a slot *s* in the other. In the adaptation shown the pin is fixed in the jack *e'* and the slot *s* is formed in the jack-lever *h'*. The slot extends from said pin *q'* 45 to the left (when the jack-lever *h'* and the jack *e'* are against their respective stops). When, now, the hooks are engaged with their knives, the slot *s* will allow some lost motion as between parts *e'* and *h'*, so that 50 jack *e'* cannot be drawn and held as far forward by its jack-lever *h'* while the same is oscillating as the jack *e* in Fig. 3 can be drawn and held forward by its jack-lever *h*. The slot is made sufficiently long so that 55 when the jack *e'* is drawn forward into the

dot-and-dash outline position in Fig. 2 its advancement to this position will be sufficient to bring No. 3 box of the box structure *A* in alinement with the plane *B*.

60 In Fig. 1, the pin *q''* is fixed in the jack *e''* and penetrates a slot *s''* in the jack-lever, said slot being formed precisely the same as the slot *s'*, except that it is extended somewhat farther to the left than the latter. This slot therefore affords greater lost motion 65 as between the jack-lever *h''* and the jack *e''* than is afforded by the slot *s'* as between the jack-lever *h'* and the jack *e'*, with the consequence that when the jack-lever *h'* is oscillating under the action of the knives, it 70 will hold its jack-lever *e''* not as far advanced as jack-lever *h'* holds the jack *e'* under the same condition. The dot-and-dash outline of the jack-lever in Fig. 1 represents 75 its position under this condition and corresponds to the position occupied by box No. 2 when alined with the plane *B*. The jacks *e*, *e'* and *e''* are connected with the box structure *A* each by its own flexible connections *t*, *t'* and *t''*, the same being passed 80 around suitable pulleys *u* and all of the same length.

85 Résumé: When, therefore, all the jacks rest against the stop *f*, box No. 1 is alined with plane *B*; when jack *e''* is drawn forward to the dot-and-dash outline position in Fig. 1, box No. 2 is alined with plane *B*; when jack *e'* is drawn forward to the dot-and-dash outline position in Fig. 2, box No. 3 is alined with plane *B*; and when jack *e* is 90 drawn forward to the dot-and-dash outline position in Fig. 3 box No. 4 will be alined with plane *B*.

95 In actual practice, the jack-levers *h'* and *h''* (which have the slots) will not usually stand engaged with both stops *i* when in their idle positions, although they are so shown in Figs. 2 and 3 for the purpose of clearer illustration; instead, each will be left standing at that time engaged with only 100 one of these stops (see Fig. 1), because the pull of the box which is exerted on the jack-lever so long as it is oscillating ceases to act on the same as soon as, on the pattern mechanism "calling" the parts to their idle 105 position, the jack comes in contact with its stop *f*. On the parts being again "called" into action, the lost motion manifests itself either in a short idle advance of the knife before it engages the hook (as the upper 110 hook and knife in Fig. 1) or in an idle shifting of the jack-lever until its unengaged end (as its upper end in Fig. 1) finds a purchase on the adjoining stop, depending of course on which knife, upper or lower, goes 115 first into action.

120 In Figs. 1 and 2 a set-screw *u* is shown at the left-hand end of each slot, whereby the extent of lost-motion may be adjusted with the purpose of bringing boxes 2 and 3 of the 125

130

box structure into accurate alinement with the plane B.

Having thus fully described my invention, what I claim and desire to secure by Letters

5 Patent is:

The combination, with normally retracted members to be moved to different positions, of a supporting structure having a stop limiting the retracting movements of said members, knives reciprocating synchronously in reverse directions and adapted to effect the movement of said members away from the stop, trains of parts adapted to transmit movement from the knives to said members

15 and each comprising hooks and a lever piv-

otally connecting said hooks and pivotally connected with one of said members, and means for controlling the hooks, one of the mechanisms comprising one of said members and the corresponding train of parts having 20 a lost-motion connection between two of the elements thereof, substantially as described.

In testimony, that I claim the foregoing I have hereunto set my hand this 7th day of December, 1909.

WILLIAM KAHRE.
